(57) **CLAIM**

The ornamental design for a suspended ceiling rail, as shown and described.

DESCRIPTION

FIG. 1 is top plan view of a suspended ceiling rail incorporating our new design;

FIG. 2 is a front end elevation view thereof, the rear end view being a mirror image of the front end view;

FIG. 3 is a right side elevation view thereof, the left side view being a mirror image of the right side view;

FIG. 4 is a perspective view of a front section thereof, viewed from in front of, to the right, and above the suspended ceiling rail;

FIG. 5 is a top plan view of a variant of the suspended ceiling rail of FIGS. 1-4;

FIG. 6 is a front end elevation view of the suspended ceiling rail of FIG. 5, the rear end view being a mirror image of the front end view;

FIG. 7 is a right side elevation view of the suspended ceiling rail of FIG. 5, the left side view being a mirror image of the right side view; and,

FIG. 8 is a perspective view of a front section of the suspended ceiling rail of FIG. 5, viewed from in front of, to the right, and above the suspended ceiling rail.

Bottom views of the suspended ceiling rails are omitted because the bottoms of the rails are flat and devoid of surface ornamentation.
